Charles N. Weill

Application May 13, 1948, Serial No. 146,346

Term of patent 14 years

(Cl. D34—11)

To all whom it may concern:

Be it known that I, Charles N. Weill, a citizen of the United States of America, residing at New York, in the county of New York and State of New York, have invented a new, original, and ornamental Design for Receptacle for Coins or Similar Articles, of which the following is a specification, reference being had to the accompanying drawing, forming part thereof.

On the drawing:

Fig. 1 shows a front view of the receptacle for coins or similar articles, embodying my new design, and

Fig. 2 a top view thereof.

I claim:

The ornamental design for a receptacle for coins or similar articles, as shown.

CHARLES N. WEILL.
